MAURICE M. KASANOF, OF NEW YORK, N. Y.

METHOD AND MEANS FOR PRODUCING BIAS FABRICS.

Application filed August 22, 1922. Serial No. 583,613.

To all whom it may concern:

Be it known that I, MAURICE M. KASANOF, a citizen of the United States of America, and a resident of the city of New York, borough of the Bronx, in the county of Bronx and State of New York, have invented a new and Improved Method and Means for Producing Bias Fabrics, of which the following is a description.

10 The invention is particularly applicable to tubular fabrics for the production of individual neckties and other individual articles and has in view to produce a bias fabric from a non-bias fabric.

15 The method and means for carrying out the invention will be readily understood from the following description of a particular embodiment of the invention.

20 Reference is to be had to the accompanying drawings forming a part of this specification, it being understood that the drawings are merely illustrative of practical examples of the invention.

Figure 1 is a plan view of my improved 25 device for use in producing bias fabrics, a portion being broken away;

Figure 2 is a cross section as indicated by the line 2—2, Figure 1;

30 Figure 3 is a view similar to Figure 2 but with the expanding element hereinafter explained omitted for the insertion of the device in a tubular fabric;

Figure 4 is a fragmentary plan view with 35 the tubular fabric in position the view showing the bias form of the fabric after having been strained from its non-bias form;

Figure 5 is a view similar to Figure 4 but at the opposite side of the fabric;

40 Figure 6 is a view similar to Figures 4 and 5 but with an additional attachment and with the bias produced in opposite directions from the medial line of the fabric;

Figure 7 is a cross section on the line 45 7—7, Figure 6;

Figure 8 is a fragmentary plan view with part broken away and showing a modification to be hereinafter referred to;

50 Figure 9 is a fragmentary perspective view of a part employed in the production of the fabric with a reverse bias as shown in Figure 6.

55 In carrying out my invention I provide a body 10 having two spaced sides united by screws or pins 11 at two separated transverse lines. Centrally of the body 10 between the

sides thereof is adapted to be disposed an elongated flat blade-expanding element 12. The element 12, which is in the form of a flat strip, has a suitable handle 13 extending straight at one end thereof. A stop pin 14 at the forward end of the device extends across the space between the sides of the body and engages the notched front end of the element 12 to limit the forward movement thereof. The element 12 furthermore has 60 a longitudinal series of holes 15 for a purpose presently explained, there being registering holes 16, 17 in the opposite sides of the body 10.

Between the sides of the body 10 adjacent 65 each side edge and at each side of the central space occupied by the element 12 when said element is in position, are expanding blades 18, 19 capable of longitudinal and transverse movement in the body. The one blade 18 has teeth 20 or equivalent roughened members to engage the fabric A when the device is inserted in a tubular fabric for a necktie for example, the opposite blade 19 having teeth 21 or their equivalent. 70

The blades 18, 19 in the form shown in Figures 1 to 3, have each an oblong slot 22 through which the screws or pins 11 pass. The longitudinal dimension of the slots 22 permits of blades 18, 19 to be moved longitudinally either in the same direction or in opposite directions in the use of the device 75 hereinafter explained while the transverse dimension permits of the blade being moved laterally to project the teeth thereof beyond the side edges of the body 10 or to withdraw the teeth within the side edges of the body. In blades 218, 219 in Figure 8 instead of oblong slots 22 a narrow slot 122 is provided 80

offset at the central portion obliquely so that the ends lie in parallel planes, a pin or screw 11 passing through slot 122, the arrangement being such that with the longitudinal movement of a blade as 18, for example, in the body 10, the oblique intermediate portion of said slot will cause a lateral movement of the blade and said pin will resist a retrograde movement laterally. 85

In order to produce a bias fabric article by 90 the aid of the described device the assemblage of Figure 3 is inserted in the tubular fabric A, for example, Figure 4, the expanding element having been withdrawn to permit the blades 18, 19 to approach each other so that the teeth 20, 21 lie within the smooth 95

side edges of the body 10. The fabric tube having been placed on the device the element 12 is again inserted to expand the blades 18, 19 causing the teeth 20, 21 to project beyond the side edges of the body and in engagement with the tube A at opposite sides. The teeth 20, 21 in Figures 4 and 5 are disposed in opposite directions, the teeth at one side being inclined forwardly and the teeth at the opposite side inclined rearwardly in order to prevent slipping of the fabric. Either of the blades 18, 19 is now moved longitudinally to give that edge of the fabric longitudinal movement, or the blades 18, 19 may be moved in opposite directions. If the elements of the design, as for example, parallel stripes as shown, are continuous about the tubular fabric then Figures 4 and 5 will merely represent opposite sides of the fabric. If the design is at one side of the fabric only then the obliquity of the design may be either forwardly from a given side edge or rearwardly from said given side edge.

With the stretching of the fabric to give it a bias character the device with the fabric thereon is subjected to steaming action by holding it over escaping steam from a steamer, the various forms of which are well known and not needing illustration. The steaming of the fabric while on the device gives permanency to the bias character of the fabric. Said fabric may be readily removed by withdrawing the central element 12 and permitting the blades 18, 19 to collapse toward each other to withdraw their teeth within the side edges of the body 10 whereupon the fabric may be readily slipped from the device.

In Figures 6, 7 and 9 means is shown whereby the bias character of the fabric may be from the medial line toward opposite sides for which purpose I provide a clamp strip 24 having its pins, 25, disposed in longitudinal series and spaced to enter the registering holes 16, 15, 17. For producing the double bias fabric the blades designated 118 and 119 have their teeth 120 and 121 inclining in the same direction.

With this form of the invention the tubular fabric designated C is placed on the device as previously described and the clamp strip 24 is applied so that its teeth 25 extend through the holes 16, 15, 17, said strip lying at the exterior of the fabric C. The two blades 119 and 120 are now moved in the same direction, the strip 24 holding the fabric immovable at the medial line. The result is that a double bias is produced in the fabric after which the fabric while still on the device is steamed for the fabric to become permanently set in the bias form. The fabric in Figures 6 and 7 is designated by the letter C.

The blades 18, 19 have at the rear end

handles 23 disposed laterally outward in opposite directions for the convenient manipulation of said blades.

I would state in conclusion that while the illustrated examples constitute practical embodiments of my invention, I do not limit myself strictly to the exact details herein illustrated, since, manifestly, the same can be considerably varied without departure from the spirit of the invention as defined in the appended claims.

Having thus described my invention, I claim:

1. In the production of bias fabric from non-bias fabric, the steps of subjecting said fabric to a lateral straining and to longitudinal straining to give it a bias character and then steaming the fabric to give permanency to the bias character.

2. A device for giving bias to a non-bias fabric, a holder for the fabric having laterally movable means at the side edges to engage the fabric, and means to expand the first means said second means being movable to give relative longitudinal movement to the fabric at the opposite edges to thus distort the fabric into bias form.

3. A device for producing bias fabrics from non-bias fabrics including a body adapted to receive the fabric, and blades supported on the body at opposite sides and having at their outer edges means to engage and laterally tension the fabric, one of said blades being movable longitudinally to carry the adjacent side edge of the fabric and give bias form to the latter.

4. A device for producing a bias fabric from a non-bias fabric, said device including a body, blades on the body at opposite sides and movable laterally toward or from each other to project the side edges beyond the sides of the body or to withdraw the same within the sides of the body, said blades having means at their outer edges to engage a fabric, and a spreader means adapted to be disposed in the body between said blades at least one of said blades being capable of movement relatively to the other to carry the fabric at the adjacent edge longitudinally relatively to the opposite side of the fabric.

5. A device for producing a bias fabric from a non-bias fabric comprising a body having spaced sides, and blades disposed between the sides of the body at opposite sides of the medial line, said blades being movable transversely to project the same beyond the sides or to withdraw the blades within the sides and said blades furthermore being movable longitudinally and having means at their outer edges to grip the fabric.

6. A device for producing a bias fabric from a non-bias fabric comprising a body having spaced sides, and blades disposed between the sides of the body at opposite

sides of the medial line, said blades being movable transversely and longitudinally and having means at their outer edges to grip the fabric; together with a spreader strip 5 adapted to be inserted in the body along the medial line between said blades.

7. A device for producing a bias fabric from a non-bias fabric, said device including a body having means to engage the fabric 10 at the side edges and to give longitudinal movement to the side edge portions of the fabric, and means to clamp the fabric along an intermediate line to give bias to the fabric by a longitudinal movement of the side portions relatively to the clamped line for 15 giving a reverse bias to the fabric.

8. A device for producing a bias fabric from a non-bias fabric, said device including a body having means to engage the fabric 20 at the side edges and to give longitudinal movement to the side edge portions of the fabric and means to clamp the fabric along an intermediate line to give bias to the fabric by a longitudinal movement of the 25 edge portions relatively to the clamped portions and thereby produce a reversed bias, said clamp means consisting of a strip having pins to engage said body.

9. A device for producing a bias fabric 30 from a non-bias fabric, said device including an elongated body, blades on the body at opposite sides of the medial line, an expanding blade element adapted to be inserted in the body between said blades, said body 35 and said expanding element having holes which register when said element is in position, the body being adapted to receive the fabric to be treated and having means at the side edges to grip said side edges of the 40 fabric, said blades being movable longitudinally to move the side portions of the fabric longitudinally for giving the fabric bias form, and a clamping strip adapted to be imposed on the fabric at the medial line of 45 the body, said strip having pins adapted to pass through registering holes of the body and expanding element.

10. A device for producing a bias fabric from a non-bias fabric, said device includ-

ing an elongated body having spaced sides, 50 pins extending through the body across the space between the sides thereof, and blades disposed between the sides of the body at opposite sides of the medial line and provided with means at their side edges to 55 grip the fabric, longitudinal slots in the blades, said pins passing through the slots and said slots being offset obliquely at an intermediate portion thereof, the blades being shiftable longitudinally in the body. 60

11. A device for producing a bias fabric from a non-bias fabric, said device including an elongated body having spaced sides, 65 pins extending through the body across the space between the sides thereof, and blades disposed between the sides of the body at opposite sides of the medial line and provided with means at their side edges to grip the fabric, longitudinal slots in the blades, 70 said pins passing through the slots and said slots being offset obliquely at an intermediate portion thereof, the blades being shiftable longitudinally in the body; together with an elongated expanding element adapted to be inserted in the body along the medial line 75 between said blades.

12. A device for producing a bias tubular fabric from a non-bias tubular fabric, said device including an elongated body adapted 80 to be inserted in the fabric, and means on the body to strain the fabric laterally and longitudinally in directions to give the same a bias character.

13. In a method of producing a bias tubular fabric from a non-bias tubular fabric, 85 the steps of straining the fabric first laterally and then straining it longitudinally from the non-bias to a bias character and giving permanent set to the bias character of the fabric. 90

14. In a method of converting a non-bias fabric into a bias fabric, the steps of straining the non-bias fabric laterally and then straining it longitudinally from its non-bias 95 character to give it a bias character, and then giving permanency to the bias character of the fabric.

MAURICE M. KASANOF.
